SAFETY DEVICE FOR STRANDERS

Carl O. Bruestle, Rahway, N. J., assignor to
Syncro Machine Company, Perth Amboy, N. J.,
a corporation of New Jersey

Application May 19, 1945, Serial No. 594,757

2 Claims. (Cl. 57—81)

1

This invention relates to improvements in stranding or cabling machines with special reference to a safety device controlled by the individual strands being formed into a cable for stopping the machine when one or more strands breaks or runs out.

A more specific object of the invention is the provision of a safety device for stranding or cabling machines comprising an electrical switch for each strand having a contact member controlled by it.

A more detailed object of the invention is the provision in such a safety device of means for rendering it inoperative when desired.

Other and more detailed objects of the invention will be apparent from the following disclosure of one embodiment thereof as illustrated in the attached drawings.

This invention resides substantially in the combination, construction, arrangement and relative location of parts as will be described in detail below.

In the accompanying drawings—

Figure 1 is a side elevational view of the front end of a strand or section with some parts broken away;

Figure 2 is a vertical, central, cross-sectional view through one of the safety devices of this invention;

Figure 3 is a cross-sectional view taken on the line 3—3 of Figure 2; and

Figure 4 is a side elevational view of the structure of Figure 3.

In the operation of stranding and cabling machines, it is desirable to have some form of safety device actuated when one or more of the strands being formed into a cable breaks or runs out to automatically stop the machine for the purpose of repairing the break or substituting a fresh package of strand material.

While it is not of special importance in relation to this invention, it is noted that stranding and cabling machines are adapted to twist two or more bare or insulated wires, respectively, into a cable as represented, for example by a stranded wire cable or a plurality of twisted insulated conductors. It will be seen from the following disclosure that the subject matter of this invention is applicable to the control of various forms of machines for feeding wires, tapes, ribbons, strands, or the like to detect breakage thereof or their running out and when desired upon detection to effect stoppage of the machine.

Referring to the drawings, there is illustrated 55

in elevation the front end of a typical stranding machine of which a supporting girder or structure 1 is a part. Mounted upon this structure by means of bearings and rollers or other suitable supports 3 is a large disc-like member 2 centrally of which is secured a shaft 3 to the end of which, not shown, power to effect rotation thereof is applied in any suitable manner. The shaft 4 has an axial passage through which a central strand or core C may be fed longitudinally to the die position D. Attached to the end of the shaft 4 is the lay plate 5 which has a series of guides or eyepieces 6 mounted therein through which the strands W to be twisted around the core 10

13 C are guided to the die position.

The forward portion of the guide tube for one of the strands is shown at 7 while the forward portion of the cradle for one of the other strands W is shown at 8. The construction of this portion of the machine is of special importance with relation to the subject matter of this invention and may take any of the forms that are known in the art of which the one illustrated is a well known type. The strands pass through passages 20 9 in the supporting disc 2 so as to deliver the strands W to the control devices which form the subject matter of this invention.

The control devices are arranged around the disc 2 on its forward face, as illustrated, so as to 25 lie in pairs at diametrically opposite positions. Thus it is possible to twist one or more pairs of strands W about the core C. At this point it may be noted that it is not necessary, as will be appreciated by those skilled in the art, to have a core wire C since one or more pairs of strands W may be twisted into spiral relationship at the die station D without the use of a core strand.

The safety device itself is clearly illustrated in Figures 2, 3 and 4. Each device consists of a base plate 10 which is attached in the opening 9 to the forward face of the disc 2 by means of cap screws 11. The guiding and protecting tube 7 telescopes into a central aperture in the supporting plate 10, as clearly shown in Figure 2. Mounted in any 30 suitable manner on the plate 10 is an insulated bushing 12 in which an electrical contact 13 is mounted so as to be insulated from the machine. Attached on or formed integral with the plate 10 are a pair of parallel arms 14 in the ends of which 35 is attached a shaft upon which the guide wheel 15 is rotatably mounted and over which the strand W passes from the tube 7. Attached to the plate 10 in any suitable manner so as to lie between the parallel arms 14 is a small bracket 16 on which 40 is rotatably mounted an S-shaped contact mem-

ber 17 formed from a rod or wire of a suitable metal. The contact is proportioned so that it may pivot on the supporting plate 16 into contact with the fixed contact 13. A coil spring 18 encircles the pivotally mounted portion of the contact 17 and is biased so as to normally urge it into engagement with the contact 13. This bias results from the fact that one end of the spring lies against the support 16 and a longer end 18' engages the contact 17. The strand W is fed through the upper loop of the contact 17, as clearly illustrated in the drawings, so that when the strand is under normal feeding tension it will hold the contact 17 in the position shown in Figure 2 against the resistance of the biasing spring 18 tending to move it in a counterclockwise direction (Figure 2) into engagement with the fixed contact 13.

The S-shaped contact 17 has its lower leg extended, as shown in Figure 3, so that it may be slid transversely in its pivotal support from the full line position shown in Figure 3 to the dotted position in the same figure. A collar 19 is secured to the extended arm of the contact so as to lie against the pivotal support when the contact is thus shifted. Attached to or forming part of the support 16 is an arm 20 having a slot extending inwardly from its upper face and an ear 21 overlying the slot as is best seen from Figures 2 and 4. When the contact 17 is in full line position it may pivot in its support under the ends of the spring 18. On the other hand, when it is shifted to the dotted line position shown in Figure 3 it lies in the slot in the arm 20 and when moved behind the ear 21 is held by the spring 18 in a slotted position out of engagement with the contact 13, as clearly shown by the righthand dotted position of Figure 2.

The normal operation of this device is already clear from the description above. When in use the strand W holds the contact arm 17 out of engagement with the contact 13 either until it is broken or runs out whereupon spring 18 moves it into engagement with the contact 13.

Since a stranding machine of this type is adapted to handle any number of pairs of strands within its capacity, it will be desirable frequently when using a lesser number of pairs than the maximum capacity of the machine to be able to render the control device 17 inoperative. Assuming for descriptive purposes that the machine is capable of handling eight pairs of strands and it is desired to twist a cable having only four pairs of strands, it is apparent that every other safety device must be rendered inoperative. In that

event the contact arms 17 are shifted to a position where they may be locked in inoperative position in the slotted arm 20. They will thus not interfere with the operation of the machine in twisting four pairs of wires.

Electrically it will be seen that the contact arm 17 is grounded on the machine forming one side of the circuit to be controlled by the safety device. The leads, not shown, for the insulated contacts 13 will be extended to a slip ring, not shown, insulated from the machine by means of which the other control circuit wire is connected through a fixed insulated brush, not shown. It is, of course, apparent that the control circuit may be used for any number of purposes as, for example, to operate a signal device or suitably constructed switches for shutting off the power which operates the entire machine so that if a strand is broken it can be repaired or if it has run out its supply reel can be replenished.

From the above description it will be apparent to those skilled in the art that the subject matter of this invention is capable of some variation without departure from the scope thereof and I do not, therefore, desire to be limited other than as required by the appended claims.

What is claimed is:

1. In a strand feeding machine, the combination including a guide member over which the strand is fed in the direction of its length, an insulated electrical contact mounted adjacent said guide member, and a movable contact arm biased towards engagement with said fixed contact and positioned adjacent the path of travel of the strand to said guide member so as to be engaged by the strand and held against its bias out of engagement with the fixed contact, whereby upon breakage or running out of the strand the movable contact engages the fixed contact, said movable contact being transversely shiftable and a locking member forming a seat therefor into which it may be shifted transversely.

2. In a strand feeding machine a stop motion switch comprising an insulated electrical contact mounted adjacent the path of travel of the strand, a movable contact arm, means for pivotally and slidably supporting said contact arm so as to be engaged by the strand, resilient means for biasing said arm into engagement with said contact when the strand breaks or runs out, and means forming a lock for holding said arm out of engagement with said contact when shifted into engagement therewith, said resilient means serving to hold said arm in said seat.

CARL O. BRUESTLE.
